C. E. Pierce.

Burglar Alarm & Lock Apparatus.

Nº 71637

Patented Dec. 3, 1867.

Witnesses;

5. Inventor;
Charles E. Pierce.

United States Patent Office.

CHARLES E. PIERCE, OF NEW YORK, N. Y.

Letters Patent No. 71,687, dated December 3, 1867.

IMPROVED BURGLAR-ALARM AND LOCK-APPARATUS.

The Schedule referred to in these Letters Patent and making part of the same.

KNOW ALL MEN BY THESE PRESENTS:

That I, CHARLES E. PIERCE, of the city, county, and State of New York, have invented certain new and useful Improvements in Burglar-Alarm Apparatus, and which I design to be used in connection with doors, gates, windows, and shutters, and to be so placed and arranged that when a door, gate, window, or shutter with which my said burglar-alarm apparatus is connected, is slightly opened or raised, an alarm will be sounded, and indicate on the dial-plate which door, gate, window, or shutter, or apartment of a building is being opened, raised, or disturbed, and at the same time lock said door, gate, window, or shutter, as case may be. The following is a full, clear, and exact description thereof, reference being had to the annexed drawings, making a part of the same, in which—

Figure 1 represents a side view of the alarm-mechanism, and

Figure 2, a top view of the same.

Figure 3 represents the dial-plate.

Figure 4 represents a front view of a case which encloses the alarm-mechanism.

Figures 5 and 6 represent the window-guards or bolts, which are to be fastened to a window-frame, and

Figures 5^a and 6^b the front and side view of a plate to be fastened to a window-sash.

Figure 6^a represents a knob to be placed on the outer ends of window-guards or bolts.

Figure 7 represents a perspective view of a bolt for doors, gates, and shutters, and

Figures 7^a and 7^b the front and side view of a plate which is fastened to the jamb of a door, gate, or shutter.

Figures 8 and 8^a represent a front and side view of a lever.

Figures 9 and 9^a represent a crank to be used in connection with the alarm-apparatus.

Figures 10, 11, 12, and 12^a represent a front and side view of rollers, to be used in connection with the alarm-apparatus.

Figure 13 represents a lever to be attached to the alarm-mechanism; L, on Figures 14, 14^a, 14^b, and 14^c, represent parts of a movement which is a part of the alarm-movement—

All of which said figures above mentioned are more minutely described and explained below.

Only one alarm-movement, with its proper attachments, on plate A, is represented in the drawings, but in the construction and application of my said burglar-alarm apparatus, as many alarm-movements, with movement L and lever O attached, may be used as desired, being careful to place each alarm-movement in suitable relation to and around the alarm-bell and arms attached to the centre-wheel, said movement and bell being fastened on plate A.

b, on figs. 5 and 6, respectively represent the arms attached to the guards or bolts for the connecting-wires or lines, and to the outer ends of which the said wires or lines may be attached. Said wires or lines may be attached to either ends of said arms b, depending upon the direction of turn given to the bolt, with which they are respectively connected.

C, on figs. 5 and 6, represent the guards or bolts for windows, and c c the knob on said bolt, which is placed on and near the end of said bolt C.

D, on fig. 6^a, is a small knob, which is to be placed or screwed on to the outer end of said bolt C, said knob D projecting through the frame and into a room, for the purpose of its being clasped hold of, or to draw said bolt-knob c c out and away from the cavity or recess in plate or figs. 5^a and 6^b; said plate being fastened to a window-sash. When said bolt-knob c c is drawn away or removed from the recess in plate on figs. 5^a and 5^b, hereinafter described, which is attached to a sash, the said sash becomes unlocked, and is free to be raised or lowered, as the case may be, without disturbing the alarm-mechanism, which is placed in a sleeping-apartment or other part of a building.

E, on figs. 5 and 6, is a plate, made of metal or other suitable material, to which the bolt C is fastened; said plate E having a slot in it, near the form of an L, and through which projects knob c c, and let into the recess or cavity in plate or figs. 5^a and 5^b, said plate being fastened to a window-sash.

F is the cavity on plate 5^a and 5^b, for knob c c to be inserted as above described, when pressure is made against knob c c, attached to the bolt C, by raising or lowering the window-sash; the object being to cause a pull to be made on the connecting-wires or lines, and operate lever O, on fig. 13, attached to the alarm-

concealing the name of a door, gate, window-shutter, or apartment of a building, which may be written or placed in its proper place on dial-plate on fig. 3.

In the use of my said alarm and lock-apparatus, it will be found more convenient and desirable to have the parts thereof which are enclosed in the case or cover, above described, placed in some convenient locality of a sleeping-room, or apartment of a building, so that when an attempt is made by a burglar or other person to open a door, gate, window, or shutter, when the said apparatus is properly adjusted, an alarm will be sounded and immediately indicate on the dial-plate the name of the door, window, gate, shutter, or apartment of a building which is being disturbed. To effect the locking of the door and alarm being sounded, also indicating on the dial-plate from whence the alarm proceeds, one end of wires or lines is attached to one end of lever O, or its equivalent attached to the alarm-movement, and the other end of the said wires or lines is fastened to the outer ends of the guards or bolts, above described; and when the knob of either of the window or door-bolts is placed in the recess or cavity in plates on figs. 5^a and 5^b, and 7^a and 7^b, said plates being fastened to a door, gate, shutter, or window, by slightly raising or lowering the window, or opening the door, gate, or shutter, it will cause the bolt to turn partially around, carrying with it the arms b' on the bolt C and C', to which the connecting-wires or lines are attached, and consequently cause said wires or lines to draw down that arm of the lever O attached to the alarm-movement with which one end of the wires or lines is connected, which raises the opposite arm of lever O, and releases the projecting part o o o from the detent-arm q', attached to spindle q', said spindle q' being attached to the alarm-movement. The projecting part o o o being inserted in clasp L², on spindle L¹, and one end of lever O being raised, of course carries with it the outer end of clasp L². The pin L³, on spindle L¹ being inserted in clasp L⁴, attached to spindle L L, causes said spindle L L to turn to the right or left, carrying with it hand G, which is fastened to the upper end of spindle L L, which projects through the dial-plate, above described. The object of said hand G being placed over the dial and attached to spindle L L, is for the purpose of revealing or concealing the name of the window, door, gate, shutter, or apartment of a building, and when arm m', attached to centre-wheel m, is moved out and away from the detent-arm q, and the projecting o o, lever O raised also out of the way of the detent-arm q, attached to spindle q', the hammer-arm P attached to spindle q' becomes free, and when the spring, attached to the alarm-movement is wound up, an alarm will be sounded, hand G turned so as to reveal on the dial-plate the name of the door, gate, shutter, window, or apartment of a building which is being disturbed and causes the alarm.

Having thus described my said alarm and lock-apparatus, and the manner in which the same is operated, what I claim as new therein, and desire to secure by Letters Patent, is—

1. I claim the combination of the bolts shown in figs. 5 and 6, with the parts 5^a, 5^b, and 6^a, operating to lock a window, in the manner shown.
2. The parts represented on figs. 14, 14^a, 14^b, and 14^c, or their equivalent, operating as described and for the purposes set forth.
3. In combination with the elements of the preceding claim, I claim the lever O, operating as described.
4. In combination with the alarm-mechanism, I claim the levers for increasing the length of movement, and the rollers, all combined as and for the purposes set forth.
5. I claim the centre-wheel M, on figs. 1 and 2, made up of parts M¹ and M², for purposes set forth.
6. I claim the bolt on fig. 7, made up of parts C', I, b', and K, for locking a door or gate, at the same time that it operates the alarm-mechanism, as described and for purposes set forth.
7. In combination with elements of the claim preceding, I claim the plates J and H, as and for the purposes set forth.
8. In combination with the parts claimed in the second and third claims, I claim the dial-plate with openings, as and for the purposes set forth.

CHARLES E. PIERCE.
